UNITED STATES PATENT OFFICE

JOSEPH FERRARA, OF BROOKLYN, NEW YORK

LABELING MECHANISM

Application filed July 21, 1931. Serial No. 552,108.

This invention relates to machines for applying printed paper labels to cylindrical surfaces, such as bottles, jars, and like containers.

One of the objects of the invention is to provide a mechanism which will operate automatically in applying an adhesive coating to the lowermost of a stack of prepared labels, convey the label into position to engage the surface of one of a plurality of bottles 10 constantly advanced upon an endless conveyor, press the label against the bottle to cause definite adherence in proper position, and eventually discharge the succession of labelled bottles upon a transverse conveyor to 15 be delivered outwardly of the machine.

A further feature is in the provision of a series of such labeling mechanisms arranged to operate side by side and deliver upon a conveyor common to all, being at a right angle 20 adjacent the delivery ends of the several units employed.

A further purpose is to produce a bottle labeling mechanism combining effectiveness with simplicity, speed of operation, and which 25 may be grouped compactly so as to occupy a minimum of space, all being under the supervision and control of a single operator.

These several advantageous objects, together with others of like nature, are accomplished by the novel design, construction and arrangement of parts, as hereinafter described and illustrated in the accompanying drawings, constituting an important component of this disclosure, and in which:

Fig. 1 is a side elevational view of an embodiment of the invention illustrating its application.

Fig. 2 is a longitudinal sectional view, taken in a horizontal plane on line 2-2 of Fig. 1.

Fig. 3 is a partial transverse sectional view taken on line 3-3 of Fig. 1.

Fig. 4 is a diagrammatic plan view illustrating the grouping of a plurality of the labeling mechanisms.

The bed 10 of the machine consists of two similar level plates 11-11' resting on beams 12-12' arranged edgewise and supported at their ends on legs 13-13' constituting a rigid 50 structure of convenient height.

Journalled in suitable bearings below the bed, at the receiving end is a shaft 14, which, if several units be used, is common to all; this shaft may be gear or belt driven, as at 15, at a reduced speed by the motor 16.

At the opposite, delivery end of the bed is another shaft 17 having fixed on its front end a bevel gear 18 driving a mating gear 19 fixed on a shaft 20 housed in a bearing 21 and driving a cross conveyer 22 by which the bottles "B" are conveyed outwardly of the machine.

Fixed on the shaft 14 are a pair of spaced sprockets 23-23' driving conveyor chains 24-24' trained over another pair of sprockets 25-25' fixed on the shaft 18 in such manner as to transmit motion to it.

The upper run of the chains 24-24' are just below and parallel with the plates 11-11' of the bed as best seen in Fig. 3.

Attached at intervals to these chains are carriers 26 adapted to engage the bottles "B" and retain them centrally on the bed as they are advanced therealong.

A bracket 28 is secured by its footings 28'-28" to the rear edge of the bed element 12', this bracket presenting an arch carrying at its raised portion a holder 29 having a plurality of labels "L" disposed therein.

On the front portion of the bracket 28 is an open topped container 30 for any preferred adhesive which is constantly agitated by a pair of spaced rolls 31 carried by a spindle 32 revoluble in the upper part of the container and driven by a wheel 33 over which is trained a belt 34 driven by a pulley 35 fixed on the rear end of the shaft 18.

A stud 36, fixed in the bracket 28, acts as a pivot for a lever 37, the forwardly reaching arm of which has pivotally engaged to it a forked lever 38 carrying a pair of rolls 39 held normally in engagement with the peripheries of the adhesive dispensing roll 31 by reason of the tension spring 40 connecting the opposite end of the lever 38 with a lug 41 of the lever 37; another lug 42 on the lever 37 acts as a stop for the lever 38 when the rolls are disengaged.

Pivottally connected with the opposite, front end of the lever 37 is an actuating arm

43, offset at 44 to extend through the bracket 28 and engaged with a crank-pin 45 fixed in a disc 46 secured on the rear-end of the shaft 14.

5 Also on the shaft 14, at the side of the sprocket 23', is another disc 46 having a cam groove 48 in which operates a cam roll 49 mounted on the shank 50 of a fork 51 straddling and guided by the shaft 14, as best seen 10 in Fig. 1.

Fixed in the form shank 50 is a bar 52 having rack teeth 53 at its raised end, the same being guided by a support 54 fixed on the bracket 28.

15 The support 54 has an extension in which is mounted a pin 55 acting as a pivot for a pinion 56 meshed with the rack, and rigid with the pinion is an arm 57, forked at its free end, and provided with a pair of pads 58 adapted to straddle a bottle "B" and engage a label "L" at its end portions.

An anvil 60, disposed centrally in the path of the on-coming bottles, is supported by a pair of spaced links 61 pivoted to a shoe 62, 25 the anvil links being pivoted to the chains 24-24' slightly in advance of the carriers 26 and normally drawn forward into operative position to engage the bottles by a tension spring 63.

30 Carried by the shoe 62 is a roll 64 adapted to ride on a cam track 65 centrally below the pathway of the chains 24-24' and level throughout its length except for a cam depression 66 which permits the anvil and links 35 to tilt forward in timed relation to the movement of the pads 58, the spring 63 materially assisting such movement which is clearly indicated by the full lines in Fig. 1, the normal, recedent position being apparent by the broken lines.

45 Thus the label is deposited on the bottle to be pressed firmly against it by further advancement of the conveyor chains, which causes the label and bottle to pass between an opposed pair of resilient wipers 67 extending inwardly from brackets 68 fixed on the outer portions of the bed elements 11-11'.

In operation, the machine being started, the crank pin 45 and arm 43 actuates the lever 50 37, causing the rolls 39 to receive a fresh supply of adhesive from the distributing roll 31 and then swing on the pivot 36 into the broken line position.

55 Before arriving at the end of the stroke of the lever 37, the arm carried pads 58 receive the adhesive by contact with the rolls 39, thereafter continuing upwardly to engage the lowermost label in the holder 29, this action being due to the cam actuated rack 53, 60 the same operating to move the pad carried label downwardly to contact the surface of the bottle as it moves forward against the anvil 60.

65 Continued forward movement of the conveyor, past the cam track depression 66, re-

leases the anvil from the labeled bottle, which is advanced between the resilient arms 67, effectually smoothing out the label and pressing it into intimate contact, thus completing the operation.

Eventually the bottles, now bearing labels, are moved off the chain conveyors upon the surface of the cross conveyor 22 and deposited outwardly of the machine ready for whatever disposition is desirable.

As seen in Fig. 4, several of the labeling machines may be arranged in parallel and all the bottles on the machine units deposited upon the cross conveyor as it is common to all.

80 From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent, is:

1. A container labeling machine comprising a bed having a raised arcuate bracket at its rear side, a driven shaft mounted transversely of the bed at one end thereof, a second shaft at the opposite end, sprockets on said shafts over which are trained a pair of chain conveyors, a holder for stacked labels carried by said bracket, a lever pivoted on said bracket, said lever having forked terminals provided with pads, cam means on the first named shaft to actuate said formed lever, means for supplying an adhesive to the pads prior to engagement with the lowermost label in said holder, carriers arranged at intervals on said conveyors to advance containers disposed on said bed between the pads of said lever, and means for holding the labels against the containers during their passage from the pads to a pair of wipers between which the containers are caused to pass.

100 2. A container labeling machine comprising a bed having a central longitudinal passage, a pair of chain conveyors movable below the surface of said bed adjacent the mentioned passage, carriers on said chains to extend upwardly through the passage to engage containers disposed on the bed, a holder for stacked labels above said bed, a pivoted arm having forked terminals provided with pads between which the containers may pass, cam actuated means for moving said lever into position to receive the label from said holder and carry it into position to engage an on-coming container, crank actuated means for supplying an adhesive to said labels, cam actuated means to press the label against the container during a part of its forward movement, resilient arms for pressing the label against the side of the container as it passes

therebetween, and a cross conveyor at the foot of said bed to receive container therefrom.

3. In a container labeling machine, the combination with a bed, travelling conveyors having carriers arranged at intervals therealong
5 adapted to move containers, a label holder, and a forked lever adapted to move from the label holder with a label into the path of the moving containers, of an adhesive receptacle, a pair of rolls revoluble therein, means for transmitting rotary motion to said rolls, a bracket carried pivoted lever, crank means for actuating said lever periodically, a formed lever pivoted in one of the arms of the first named lever, rolls carried by the forks of the last named lever, resilient means for pressing said rolls against the rolls in the adhesive receptacle and means for limiting the action of said spring, said lever carried rolls being
15 movable to pass over the surface of the label carrying lever prior to its engagement with a label in said holder.

Signed at New York, in the county and State of New York, this 18th day of July,
25 1931.

JOSEPH FERRARA.
